UNITED STATES PATENT OFFICE.

NATHAN P. DAZEY, OF ST. LOUIS, MISSOURI.

DESIGN FOR A CHURN-DASHER.

60,016.

Specification for Design.

Patented Dec. 20, 1921.

Application filed February 3, 1921. Serial No. 442,304. Term of patent 14 years.

To all whom it may concern:

Be it known that I, NATHAN P. DAZEY, a citizen of the United States, residing in the city of St. Louis and State of Missouri, have invented a new, original, and ornamental Design for Churn-Dashers, of which the following is a specification, reference being had to the accompanying drawing, forming part thereof.

Figure I is a top or plan view of a churn dasher, showing my new design.

Fig. II is a side elevation thereof.

I claim:

The ornamental design for a churn dasher, as shown.

NATHAN P. DAZEY.
